CLAIM

The ornamental design for an electrical connector, as shown and described.

DESCRIPTION

FIG. 1 is a top, left, front perspective view of an electrical connector showing our new design;

FIG. 2 is a bottom, right, rear perspective view of thereof;

FIG. 3 is a bottom, left, front perspective view thereof;

FIG. 4 is a top, right, rear perspective view thereof;

FIG. 5 is a bottom, left, rear perspective view thereof;

FIG. 6 is a front elevation view thereof;

FIG. 7 is a rear elevation view thereof;

FIG. 8 is a right side elevation view thereof;

FIG. 9 is a left side elevation view thereof;

FIG. 10 is a top plan view thereof;

FIG. 11 is a bottom plan view thereof;

FIG. 12 is a top, left, front perspective view of an electrical connector showing another embodiment of our new design;

FIG. 13 is a bottom, right, rear perspective view of thereof;

FIG. 14 is a bottom, left, front perspective view thereof;

FIG. 15 is a top, right, rear perspective view thereof;

FIG. 16 is a bottom, left, rear perspective view thereof;

FIG. 17 is a front elevation view thereof;

FIG. 18 is a rear elevation view thereof;

FIG. 19 is a right side elevation view thereof;

FIG. 20 is a left side elevation view thereof;

FIG. 21 is a top plan view thereof;

FIG. 22 is a bottom plan view thereof;

FIG. 23 is a top, left, front perspective view of an electrical connector showing another embodiment of our new design;

FIG. 24 is a bottom, right, rear perspective view of thereof;

FIG. 25 is a bottom, left, front perspective view thereof;

FIG. 26 is a top, right, rear perspective view thereof;

FIG. 27 is a bottom, left, rear perspective view thereof;

FIG. 28 is a front elevation view thereof;

FIG. 29 is a rear elevation view thereof;

FIG. 30 is a right side elevation view thereof;

FIG. 31 is a left side elevation view thereof;

FIG. 32 is a top plan view thereof; and,

FIG. 33 is a bottom plan view thereof.

(Continued)

The Dash-Dash broken line portion of the figure drawings is included to show portions of the article that form no part of the claimed design. The Dash-Dot broken line portion of the figure drawings is included to show claim boundaries that form no part of the claimed design.
